UNITED STATES PATENT OFFICE.

ADOLPH MUEHLMATT, OF NEWPORT, KENTUCKY.

DESIGN FOR AN ENGRAVER'S BLOCK.

42,397.

Specification for Design.

Patented Apr. 9, 1912.

Application filed February 6, 1911. Serial No. 607,003. Term of patent 14 years.

To all whom it may concern:

Be it known that I, ADOLPH MUEHLMATT, a citizen of the United States, residing at Newport, in the county of Campbell and State of Kentucky, have invented a new, original, and ornamental Design for an Engraver's Block, of which the following is a specification, reference being had to the accompanying drawing, forming part thereof.

Figure 1 is a perspective view, and Fig. 2 is a plan view of the engraver's block.

I claim:

The ornamental design for an engraver's block, as shown.

ADOLPH MUEHLMATT.

Witnesses:

R. B. ZERFEY,
MARSTON ALLEN.
